Des. 195,448
Patented June 11, 1963

195,448

HAIR DRYER BLOWER

William J. Rakacy, Clifton, N.J., assignor to Ronson Corporation, Woodbridge, N.J., a corporation of New Jersey

Filed Nov. 30, 1962, Ser. No. 72,666

Term of patent 14 years

(Cl. D86—10)

Fig. 1.

Fig. 2.

Fig. 3.

FIG. 1 is a top plan view of a hair dryer blower showing my new design;

FIG. 2 is a front elevational view thereof; and

FIG. 3 is a side elevational view thereof.

The side not shown is similar to FIG. 3, and the rear is substantially plain.

I claim:

The ornamental design for a hair dryer blower, as shown and described.
